UNITED STATES PATENT OFFICE.

BEVERLY W. DUNN, OF PHILADELPHIA, PENNSYLVANIA.

SHRAPNEL.

SPECIFICATION forming part of Letters Patent No. 735,658, dated August 4, 1903.

Application filed July 12, 1902. Serial No. 115,276. (No model.)

To all whom it may concern:

Be it known that I, BEVERLY W. DUNN, of the United States Army, a citizen of the United States, residing at Philadelphia, in the county of Philadelphia and State of Pennsylvania, have invented a certain new and useful Improvement in Shrapnel, of which the following is a full, clear, and exact description.

At present it is the preferred practice to construct a shrapnel in such way that the case with its contained missiles and a bursting charge of powder in rear of the missiles will remain intact until the desired point of attack is reached, at which time the missiles will be discharged without rupture of the case and with practically the full effective force of the contained powder charge. Another consideration of importance is to make the number of effective missiles as large as possible, which requires that the case and other parts of the shrapnel be as light as possible.

The object of this invention is to meet the conditions above mentioned and others; and to this end the invention consists of a shrapnel having a case of substantially uniform cross-section throughout and containing a powder charge supplied by compressing the powder within the case, said charge having an opening which is provided with loose powder which is accessible by the fuse for igniting the compressed charge. In this construction instead of separating the powder from the missiles by a heavy diaphragm of metal supported on a shoulder forged or machined on the interior of the case, which shoulder increases unnecessarily the weight of the case, such as has heretofore been used, I am able to use a comparatively thin and light diaphragm, and the missiles may be superposed upon this diaphragm, with the compressed powder as a base, without danger from inertia of the balls or missiles at the moment of the shock of discharge, all as I will proceed now more particularly to set forth and finally claim.

45 In the accompanying drawings, illustrating my invention, in the several figures of which like parts are similarly designated, Figure 1 is a longitudinal section illustrating one embodiment of the invention, and Fig. 2 is a transverse section taken substantially in the plane of the line A B, Fig. 1.

The case 1 in the preferred construction is

of drawn steel of substantially uniform cross-section and having a polyhedral chamber. This case has a relatively thicker base 2 and 55 an upper screw-threaded and shouldered portion 3 to receive a disk 4, preferably of sheet-steel, and the head 5 of suitable construction and containing the time fuse.

The powder charge 6 is formed in the base 60 of the shell by introducing loose powder and compressing the same under a total pressure about fifty per cent. greater than that due to the setback of the balls or missiles from the shock of the discharge of the propelling powder charge. This compressed powder charge 6 is made with a central aperture, which is provided with an igniting charge 7 of loose powder. Above the charge of compressed powder and charge of loose powder is laid a 70 sheet or disk 8 of tin-foil or other similar or equivalent material to keep the loose powder in place and protect it from moisture, and above this is arranged a comparatively thin diaphragm 9, of steel, within which is placed 75 the diaphragm-plug 10, upon which is erected a central tube 11, which may be made of paper, extending up through the diaphragm 4 and into the head, so as to form a communicating channel from the fuse to the powder 80 charge in the base of the case. The balls or missiles 12 are stacked or piled one upon another in regular order or series around the tube 11 and rest upon the diaphragm 9 and covered in by the diaphragm 4 under restraint 85 of the head 5.

The case is provided with any usual or approved form of band 13. The interior of the case is made polyhedral and preferably hexagonal in order to receive and contain the 90 largest possible number of balls or missiles and to cause them to rotate with the case when fired from the gun.

In former constructions where a loose powder charge is used the diaphragm supporting 95 the balls above the powder has to be very heavy in order to resist the inertia of the balls at the moment of the shock of discharge, and even then the diaphragms are badly distorted. By compressing the powder charge, as herein stated, not only is it possible to use a greater powder charge in a given volume, but the compressed charge is in effect an auxiliary diaphragm to the metal diaphragm, serving to re-

sist the crushing effect of the balls or missiles at the moment of discharge, and also so support the balls as to prevent the distortion of the diaphragm. Again, the compressed powder burns more slowly than loose powder, and therefore the pressure is maintained during the passage of the diaphragm throughout the whole length of the case, acting in this respect more like smokeless powder in the modern gun, with a corresponding diminution of the tendency of the interior pressure at the moment of ignition to rupture the case. As already intimated, it is not desired that the case should be ruptured, but should act as a portable shotgun-barrel, the balls being projected to the front with an increased velocity at the point of bursting.

Other advantages of the construction are that the case, having walls of uniform section throughout, may be manufactured more cheaply and a very much lighter case and diaphragm may be employed, and thus a projectile of relatively the same weight may be constructed in which a larger number of missiles may be employed, resulting in a corresponding increase in the efficiency of the projectile as a shrapnel.

Of course it is possible to use the compressed powder charge in a case having the walls of its powder-chamber of greater thickness than the remaining walls with or without change of thickness in the diaphragm.

In my Patent No. 631,703, dated August 22, 1899, I have shown a polygonal or prismatic case and pointed out its advantages, and in my Patent No. 631,702, of the same date, I have shown jacketed balls or missiles, such as those herein shown and which I preferably use, and have pointed out the advantages of such construction, it being understood that the center or core of the missile is of lead or other suitable metal and incased in a steel

jacket; but of course I do not limit the present invention to the hexagonal form of case or to the use of jacketed missiles.

45

The advantages of using a compressed instead of a loose powder charge would apply with equal force to that form of shrapnel which comprises a case with circular cross-section and lead balls unprotected by steel jackets.

50

What I claim is—

1. A shrapnel, having a case and the powder charge compressed in the base thereof.
2. A shrapnel, having a case whose interior cross-section is uniform throughout, and a powder charge compressed in the base thereof.
3. A shrapnel, having a case, a powder charge compressed in the base thereof, and a central aperture in said compressed powder charge containing a loose ignition charge.
4. A shrapnel, having a case, a powder charge compressed in the base thereof, a loose ignition charge within the compressed charge covered by a waterproof disk and a relatively thin diaphragm, and superposed missiles supported by the diaphragms and compressed powder charge.

5. A shrapnel, having a case with a polyhedral interior, a powder charge compressed in the base thereof, a superposed diaphragm, and series of missiles stacked symmetrically within said case upon the diaphragm and compressed powder charge as their support.

6. A shrapnel, having a case provided with a slow-burning powder charge formed by compressing the powder within the base of said case.

In testimony whereof I have hereunto set my hand this 7th day of July, A. D. 1902.

BEVERLY W. DUNN.
